[57] CLAIM

The ornamental design for a smart card with two external contact regions, as shown and described.

DESCRIPTION

FIG. 1 is a top plan view of a smart card with two external contact regions showing my new design;
FIG. 2 is a bottom plan view of the card shown in FIG. 1;
FIG. 3 is a front elevational view thereof;
FIG. 4 is a rear elevational view thereof;
FIG. 5 is a side elevational view of my design as viewed from the left side in FIG. 1; and,
FIG. 6 is a side elevational view of my design as viewed from the right side of FIG. 1.
